Primary Examiner — Cathron Brooks*Assistant Examiner* — Christian P McLean(74) *Attorney, Agent, or Firm* — Thomas A. Dougherty(57) **CLAIM**

The ornamental design for a display screen with icon, as shown and described.

DESCRIPTION

FIG. 1 is a front view of a display screen with icon; and, FIG. 2 is an enlarged front view of the design shown in FIG. 1.

The outermost broken lines illustrate a mobile device and form no part of the claimed design. The remaining broken lines illustrate portions of the display screen, and portions of the graphical user interface, and form no part of the claimed design.

1 Claim, 2 Drawing Sheets(56)
